UNITED STATES PATENT OFFICE.

JAMES C. SOENKSEN, OF AURORA, ILLINOIS.

ADVERTISING-SIGN DISPLAY EQUIPMENT FOR PASSENGER CARS.

Application filed September 29, 1921. Serial No. 504,187.

To all whom it may concern:

Be it known that I, JAMES C. SOENKSEN, a citizen of the United States, residing at Aurora, in the county of Kane and State of Illinois, have invented certain new and useful Improvements in Advertising-Sign Display Equipments for Passenger Cars, of which the following is a specification.

My invention relates to advertising-sign display equipment for passenger cars and provides means whereby the advertising signs that ordinarily are held in stationary racks are caused to travel along the car, thus to enable all the signs to be read by a maximum number of passengers. The signs are connected with an endless conveyor running in a display course and doubling back on a return course, so that approximately half of the signs are displayed at all times and thus, while only the usual number of signs are in view at any one time, the sign-accommodating capacity of the car may be nearly doubled.

Among the objects of my invention are to provide simple, inexpensive and effectively working mechanisms, easy to manufacture and install, and not liable to get out of order, for holding and moving the signs and also to construct such mechanisms available for installation in passenger cars in the same location and under substantially the same conditions that now affect the use of the stationary signs.

In the drawings wherein I have illustrated a single embodiment of my invention for purposes of disclosure, Fig. 1 is a fragmentary sectional view, lengthwise of the car, equipped with the display mechanism in accordance with my invention; Figs. 2, 3 and 4 are details of casing construction; Fig. 5 is a cross-section on line 5—5 of Fig. 1; Fig. 6 is a vertical section on line 6—6 of Fig. 1; Fig. 7 is a detail of a sign holder; Fig. 8 is a horizontal section, with parts broken away, on line 8—8 of Fig. 1; Fig. 9 is a similar view showing the transfer parts in another position; Fig. 10 is a detail of the switch mechanism seen in Figs. 6 and 9; Fig. 11 is a section on line 11—11 of Fig. 1; Fig. 12 is a section on line 12—12 of Fig. 11, and Fig. 13 is a section on line 13—13 of Fig. 5.

Since street car signs are usually placed in the curved bays of the car above the windows, I show my mechanism, in detail, adapted for just such installation in a

curved "sign-bay", the space requirement for my device being substantially the same in length and width as that for the commonly-used stationary card-rack, but my device being deeper than a rack. 60

In general I provide an open faced casing 20 shaped to fit in the curved bay of the car and affording guidance, as by the front and rear guides or track-ways 21—21', 65 22—22' (see Fig. 5) at its top and bottom, for the display course and the return course, respectively, of the sign-frames 23. These frames are conveyed in endless circuit by a flexible conveyor, such as the chain 24 running on horizontally disposed sprockets 25 and 25', the former being driven in any suitable fashion, as from the car axle 26 through suitable connecting mechanism 27. The sign-frames, conveyor, and their connections 70 75 constitute what I term the traveling system.

While guided in the said trackways the signs run in parallelism with the casing axis, but at each end, where the conveyor 80 passes around a sprocket, the trackways terminate and the sign frames have to be transferred from one trackway to the other. Therefore, adjacent each end of the chain-flight I provide a transfer station equipped 85 with mechanism governing the transfer of the sign-frames from one trackway to the other; one such transfer mechanism receiving each sign-frame as it arrives at its terminus of display-course-travel, and governing 90 its transfer to the return trackway, while the other transfer mechanism correspondingly receives each sign frame as it completes 95 its travel of the return course and controls its transfer to the display track. These transfer mechanisms I so arrange that they are operated automatically from parts of the traveling system.

To describe in detail the specific travelling system shown, each sign 30 is sprung into a frame 23 that, as shown in Fig. 7, may have lower and upper grooved rails 31, 31', lipped end pieces 32, and backing strips 33, these parts being shaped suitably to hold the card in the curved condition corresponding with the curvature of the car-bay. Each of these sign-frames has in its bottom rail a single central recess 34 (see Fig. 5) pivotally engaged by a pin 36 projecting from the chain 24 the pin being preferably an elongated 100 pintle of the chain. Obviously the chain 105 performs only a tractive function with re-

spect to the frames, guidance of the frames being afforded by the ways 21, 21', and 22, 22', but the pins 36 may conveniently be utilized, as an actuating part carried by the 5 chain to control the transfer devices to be described. The trackways are formed in wooden foot and head blocks 37 and 38 respectively, that effectively constitute part of the casing 20. The blocks may extend 10 throughout the length of the casing except where cut away to accommodate transfer mechanisms; but the blocks are trackless where they extend over the transfer-stations. Conveniently a partition plate, or plates, 39 15 co-extensive with the foot and head blocks is sprung between them, assisting in holding them in place and dividing the casing into a forward or display compartment and a rear or return compartment (see Fig. 5) but this 20 is not essential.

The head block 38 is simply grooved for sign-frame guidance and the foot block 37 is counter-grooved below the trackways, as 25 at 40, to accommodate the chain. At the transfer stations where these blocks are cut away, in whole or in part, to give space for the transfer mechanisms thin metal bearing-plates 41, 42 at the bottom, and bearing plates (distinguished by a prime mark) at 30 the top are connected with the walls of the casing in any suitable fashion, and wear plate 43 may protect suitable parts of the wood surface 37' (see Fig. 12). Of course this sort of simple provision for support of 35 the transfer-mechanisms may be substantially the same at both ends of the casing and may be widely varied in structural detail.

One of the sprockets, 25' (see Fig. 12) is 40 mounted for chain-tightening movement, it being disposed on a bracket 44 extending through an aperture 45 in the bottom of the casing, and engaged by an adjusting screw 46 carried by an external bracket 47 with respect to which the sprocket-carrying 45 bracket 44 may slide. The other, or driving, sprocket 25 is mounted on shaft 49 that also carries a worm gear 50 meshing with the worm 51 carried by a suitably supported 50 jack-shaft 52, the latter having a gear 53 mounted near its end. Gear 53 meshes with gear 54 that is journaled in a bracket 55 pivotally suspended on the jack shaft 52, the spindle 54' of gear 54 having a squared end 55 for engagement with a detachable coupling 56 forming a terminal of a flexible shaft 57 that, as part of the driving connection 27, is operatively connected with the worm gear 58 driven by a worm 59 on the axle 26 of 60 the car. Of course as the car moves forward the connection, indicated in general by 27, drives the chain accordingly, and the chain, through its pin engagement with the sign frames, must carry them around the chain- 65 circuit.

Considering now the transfer mechanisms, it will be understood that these are substantially alike at the two stations and that either mechanism is capable of transferring from rear track to front track or from front track to rear track, accordingly as the chain is driven in one direction or the other (as by the running of the car forwardly or backwardly). The mechanisms are arranged and timed, however, so that with the chain running in a direction as indicated by arrows in Fig. 1 the left-end mechanism always transfers from the rear trackway to the front and the other transfers from the front to the rear trackway. Each transfer mechanism includes an open-ended carrier 60 that consists of confrontingly-channeled bottom and top rails 61, 61' so mounted and connected that the only permitted movement of the carrier is one maintaining its two rails substantially in parallelism with the trackways. As a sign-frame approaches transfer position its end enters a carrier; then as the conveyer pin swings around the sprocket, the transfer carrier holds the sign-frame, now free from track-guidance, in parallel relation to the casing axis and steers the sign-frame into alignment with the other trackway, to be drawn into such trackway by the chain.

Specifically, each rail has near its two ends a pair of pins 63, 64 engaging respectively a slot 65 in lever 66 and a pin hole in lever 67, these levers being mounted on pivots 68 and 69, borne by plate 41, and at their meeting or shorter ends making disc-and-slot engagement, as at 70. Thus, one end of the rail cannot be moved without substantially coincident movement of the other end of the rail. Likewise to insure that the top and bottom rails shall move in unison at all times, vertical levers 71 and 72 (Fig. 6) are provided to connect them, these being mounted on suitable pivots between bearing plates 73 and the ends of casing 20, such levers making disc and slot connection as at 74 with each other, and the extremity of each said lever having a fork 75 to engage the appropriate bottom or top rail as shown. It will be understood that these several sets of lever connections form one desirable means for insuring a predetermined, unison movement of the rails of the carrier, readily responsive to actuation.

Each of the lower transfer rails has an end fork 77 disposed just over the lower chain where it passes around its sprocket, this fork being arranged to cooperate with any sign-frame-carrying pintle 36 on the chain, as a convenient part of the traveling system to govern the operation of the carrier. When receiving the pin 36, the fork lies between the chain and the sign frame, and one end of the sign frame projects into the transfer carrier 60.

Now it will be apparent that, viewing Fig. 9 and assuming the chain to be traveling in the direction of the arrow, an extension-pintle 36, standing at the point "x", will be presenting to the open edge of the carrier a sign frame 23 that is long enough to reach substantially the point marked "y". As the chain progresses this sign frame 23 is propelled into the rail-channels of the carrier 10 until its forward end reaches practically the remote extremity of said rails. At this time pintle 36 aforesaid enters the notch of the fork 77 and at the same time begins to turn around the sprocket wheel. As it progresses, 15 said pin carries the fork 77 towards the rear of the casing, and (aided by the engagement of the sign frame with the carrier) the several lever-sets heretofore described cause both rails to be moved rearwardly, equally, 20 and always in parallel relation to the axis of the casing, until the rails arrive at the "transfer position" shown in Fig. 8, aligning with the return trackway 22-22'. Consequently as the pin 36 now moves out of the 25 fork (a slight return movement is indicated to have taken place in Fig. 8) the sign-frame starts its travel along the rearward guideway or return course. It will be apparent that up to the time that it starts on its return course the sign is fully displayed, and it will not be entirely overlapped and hidden by the next succeeding sign until the pin 36 has moved to the position marked "z" (Fig. 8). The sign-frame newly introduced into the return course will, however, 30 disengage itself from the channel-rails of the transfer carrier before the carrying-pin 36 reaches point "z"; its disengagement from such channel occurring when the pin 36 has 35 reached approximately the point "z'". In short, because the carrier rails are somewhat less than half as long as a sign frame, one sign frame leaves the transfer carrier a material time before the next on-coming sign frame is ready to engage the carrier.

The transfer mechanism as thus far described is supplemented with means for restoring the transfer carrier to its initial position during the idle time when the carrier 50 is free from engagement with any sign-frame. This I accomplish, in the specific mechanism shown, by providing a snap-over switch 79 operable by the frame-carrying pintles 36, and set to be operated automatically between the time that one sign-frame leaves its engagement with the transfer carrier and the time that the next approaching sign-frame is positioned to engage the transfer carrier, and said snap-over switch having operative connection with the transfer carrier to shift the latter from transfer position back to receiving position. Specifically, 55 80 is a switch-disc with two projecting forks 81, this disc pivoted as at 82 between the courses of the chain approximate-

ly opposite the point "z" (Fig. 8) where two sign-frames, respectively approaching and receding from transfer position, will be in register, so that its forks may cooperate with two pintles 36 simultaneously. This disc 70 has a crank pin 83 connected by link 84 with a crank arm 84' that projects from a suitable lever 66 of the lever-system appurtenant to the bottom transfer rail. Manifestly as the disc is swung from the position shown in Fig. 8 to that shown in Fig. 9 it will actuate the lever system of the carrier to shift the transfer-carrier rails accordingly. To give the disc a desirable snap action I provide a snap-over spring 85 in a tubular socket 86 pivoted as at 87, the spring surrounding and bearing against a socket-guided stem 88 that has its head pivotally connected with the crank pin 89 on the disc. It will be understood that the snap-over switch would work 80 practically as well with only one fork 81, but the duplication lightens the work on the fork and decreases liability to breakage.

The containing casing 20 takes any form requisite to fit in the portion of the car allotted to the display, and to invest entirely the mechanism described, leaving only the display opening uncovered. It is most conveniently made of sheet metal, and to facilitate introduction and removal of signs it 90 may be made with part of its top and front lip cut away, and supplied with a detachable cover portion of substantially a sign length, the cover being located, preferably, at the end adjacent the driving gearing for the chain. This removable cover, indicated generally at 20' in Fig. 1 has one end provided with a tongue 90 (Fig. 2) to engage a slot 91 in the body of the casing, and at its other end has a latch-piece 92 having a stem 93 95 slideable with respect to a slot 93 so that the latch may engage or disengage a receptive edge 94 of the casing top and be secured in retaining position by a wing nut 95. When changing signs the attendant disconnects the 100 slip-coupling 56 in the driving train, swings the bracket-carried gear 54 to such position that he can engage a wrench with its spindle 54' and work the conveyor chain by hand. After removing the cover member 105 110 he can bring each frame forward to the transfer position most readily to change the sign displayed therein.

In brief résumé of the operation of the device, a car-axle-driven train 27 communicates motion to the drive sprocket 25 (Fig. 6) for the conveyor chain that runs in endless course along the front and back of the casing from one transfer station to the other. This chain through its extended pintles 36 moves the sign-carrying frames along their trackways that extend between the trackless transfer stations, only the signs progressing 115 along the forward guideway being displayed, of course. As each sign frame ap-

proaches a transfer station it runs out of the trackways but enters into the top and bottom channeled rails 61, 61' of the transfer frame 60, so that when a sign transfer occurs nearly half of the sign frame is in the embrace of the transfer carrier. To effect the transfer, the pintle 36 appurtenant to the sign-frame in question engages the projecting fork 77 of the lower rail of the transfer frame, and as the pintle swings around sprocket 25' the transfer frame is carried along from front to back of the casing, thus lining the transferred sign-frame up with the return trackway into which the sign frame is then drawn by the chain. In this movement of the transfer-carrier its rails are always maintained in substantial parallelism with the casing axis. The just transferred sign frame fully leaves the transfer-carrier when the extended, sign-carrying pintle 36 is in approximately the position indicated at "z" in Fig. 8, at which time the next on-coming sign-frame has not yet come into position to engage the transfer-carrier, its pintle 36 being still considerably to the left of the point marked "x" in Fig. 9. The two pintles 36 for the just transferred sign-frame and for the on-coming sign-frame, respectively, now engage the two forks 81 of the switch mechanism shown in Fig. 10, and as the chain progresses they snap the switch mechanism over, link 84 forcing over the crank 84' of the parallel-link-motion system that connects the rails of the transfer carrier. Thus the transfer-rails are thrown forward to receptive position in timely season to receive the next on-coming sign-frame. The cycle of operations described is recurrently performed at each transfer station, the mechanisms of the two stations being substantially duplicates. To load the frames one detaches the cover 20', if need be, and (if the car be standing still) he disconnects coupling 56 and, with any suitable tool, turns gear spindle 54' by hand to bring the sign frames opposite the uncovered opening.

It will be understood by those skilled in the art that while I have described in considerable detail a particular embodiment of my invention which I regard as advantageous in respect of many of its specific features that I may claim, I do not intend to limit invention in its broader aspects to the details set forth, as many changes may be made within the spirit of my invention and within the scope of the appended claims.

I claim:

1. In a moving-sign equipment, a casing having display and return trackways and trackless transfer stations at its ends, an endless conveyor following the trackways and crossing the transfer stations, signs movable by the conveyor and guided by the trackways, a transfer carrier at each trans-

fer station, and means for positively and automatically moving said carrier from register with one trackway to register with the other trackway, alternately.

2. In a moving-sign equipment, a casing having display and return trackways and trackless transfer stations at its ends, an endless conveyor following the trackways and crossing the transfer stations, signs movable by the conveyor and guided by the trackways, a transfer carrier at each transfer station, and means actuated by the conveyor for moving said carrier into register with said two trackways alternately.

3. In a moving-sign equipment, a casing having display and return trackways and trackless transfer stations at its ends, an endless conveyor following the trackways and crossing the transfer stations, signs movable by the conveyor and guided by the trackways, a transfer carrier at each transfer station adapted to receive a sign from one trackway and move therewith to present the sign to the other trackway, and means actuated by said conveyor for positively shifting the transfer carrier back to receiving position.

4. In a moving sign equipment, a casing having display and return trackways and trackless transfer stations at its ends, an endless conveyor following the trackways and crossing the transfer stations, signs having single-point pivotal connection with and movable by the conveyor and guided by the trackways, a transfer carrier at each transfer station adapted to receive a sign and move therewith to present the sign to the other trackway, and means operated from parts carried by the conveyor for automatically restoring the carrier to receiving position.

5. In a moving-sign equipment, a casing having display and return trackways and trackless transfer stations at its ends, an endless conveyor following the trackways and crossing the transfer stations, signs movable by the conveyor and guided by the trackways, and a transfer carrier at each transfer station adapted to receive a sign and move therewith to present the sign to the other trackway, and means for constraining the carrier to move in substantially constant-parallelism with the trackways.

6. In a moving-sign equipment, a casing having display and return trackways and trackless transfer stations at its ends, an endless conveyor following the trackways and crossing the transfer stations, signs movable by the conveyor and guided by the trackways, and a transfer carrier at each transfer station adapted to receive a sign and move therewith to present the sign to the other trackway, comprising interconnected links.

7. In a moving-sign equipment, an open-front casing, an endless conveyor therein making a circuit with parallel front and rear courses, sign frames connected for travel with the conveyor, means for holding the frames parallel with the conveyor, in travel along its said courses, and at each end of the conveyor circuit a transfer-carrier disposed to receive the sign-frames approaching along one course and present them properly to move along the other course, and means actuated by the conveyor for positively moving said transfer carrier from its one said position to the other alternatively.

8. In a moving-sign equipment, an open-front casing, an endless conveyor therein making a circuit with parallel front and rear courses, sign frames connected for travel with the conveyor, means for holding the frames parallel with the conveyor in travel along its said courses, and at each end of the conveyor-circuit a transfer-carrier disposed to receive the sign-frames approaching along one course, means to constrain the carrier to move with the sign into alignment with the other course, and means to restore the carrier to initial position.

9. In a moving-sign equipment, an open-front casing, an endless conveyor therein making a circuit with parallel front and rear courses, sign frames connected for travel with the conveyor, means for holding the frames parallel with the conveyor in travel along its said courses, and at each end of the conveyor-circuit a transfer-carrier disposed to receive the sign-frames approaching along one course and automatic means for moving the carrier to transfer each frame successively to the other course.

10. In a moving sign equipment for passenger cars, a casing, front and rear guides therein terminating short of the casing ends, transfer carriers beyond the ends of the guides, an endless conveyor paralleling the guides and crossing from one to the other guides adjacent to the carriers, means for driving said conveyor, sign frames each having a sign in pivotal connection with the conveyor, and conveyor-controlled means for operating each carrier to transfer sign frames successively from one guide to the other.

11. In a moving-sign equipment for passenger cars, a casing having longitudinal front and rear trackways and trackless transfer stations at its ends, an endless conveyor following the trackways and crossing the transfer stations, a series of track-guided sign frames each having a central pin-connection with the conveyor, and at each transfer station a carrier comprising upper and lower rails adapted to receive the end portion of a sign frame and movable in unison between positions aligning with the two trackways, means operable during engage-

ment of a sign frame with the carrier for moving the latter in one direction, and means operable while the carrier is disengaged from the sign-frames for moving it in the other direction.

12. In a moving-sign equipment for passenger cars, a casing having longitudinal front and rear trackways and trackless transfer stations at its ends, an endless conveyor following the trackways and crossing the transfer stations, a series of track-guided sign frames each having a central pin-connection with the conveyor, and at each transfer station a carrier comprising upper and lower rails adapted to receive the end portion of a sign frame and movable in unison between positions aligning with the two trackways, said carrier movable in one direction with the sign frame, and means operable by a conveyor-carried part for restoring the carrier in the other direction after the sign-frame has disengaged the carrier.

13. In a moving-sign equipment for passenger cars, a casing having longitudinal front and rear trackways and trackless transfer stations at its ends, an endless conveyor following the trackways and crossing the transfer stations, a series of track-guided sign frames each having a central pin connection with the conveyor, and at each transfer station a carrier comprising upper and lower rails adapted to receive the end portion of a sign frame and movable in unison between positions aligning with the two trackways, said carrier movable in one direction with the sign frame and means, including a switch operable by a conveyor carried part, and operatively connected with the carrier, for restoring the carrier after the sign-frame has disengaged it.

14. In a moving-sign equipment of the character described, the combination of a casing having front and rear trackways terminating short of the casing ends, and having a displaceable portion to give access to the sign-frames for insertion and removal of signs, a conveyor making a circuit paralleling the trackways and crossing over beyond their ends, a series of sign frames connected with the conveyor and moved in circuit thereby, driving means for said conveyor including a separable coupling adjacent to the displaceable portion of the casing for the purpose specified.

15. In a moving sign equipment, a plurality of signs, an elongated casing therefor, a conveyor for moving said signs in endless circuit longitudinally of the casing and to which said signs are connected for constant travel at spaced intervals, and means for maintaining each of said signs always substantially parallel with the longitudinal axis of the casing.

16. In a moving sign equipment, the com-

bination of a casing, an endless conveyor therein running horizontally over end wheels, guides paralleling the straight courses of the conveyor, signs engaging the conveyor running in said guides, and at each end of the conveyor flight transfer mechanism comprising a sign-receptive car-

rier movable with the sign from register with one guideway to the other, and a switch operable by a conveyor-carried part 10 operatively connected with the transfer carrier to return it to sign-receptive position.

JAMES C. SOENKSEN.
